(No Model.)

H. REMBERT.

FIRE PLACE.

No. 279,433.

Patented June 12, 1883.

UNITED STATES PATENT OFFICE.

HENRY REMBERT, OF WILLIS, TEXAS.

FIRE-PLACE.

SPECIFICATION forming part of Letters Patent No. 279,433, dated June 12, 1883.

Application filed December 19, 1882. (No model.)

To all whom it may concern:

Be it known that I, HENRY REMBERT, a citizen of the United States, residing at Willis, in the county of Montgomery and State of Texas, 5 have invented certain new and useful Improvements in Fire-Places; and I do hereby declare that the following is a full, clear, and exact description of the same, reference being had to the annexed drawings, making a 10 part of this specification, and to the letters and figures of reference marked thereon.

Figure 1 of the drawings is a perspective view of my invention; Fig. 2, a longitudinal section of the same, and Fig. 3 a cross-section taken on line *y y* of Fig. 2.

The present invention has relation to that class of fire-places provided with an air-space around its back, sides, and under its hearth, whereby the air in said space is heated and 20 used for ventilating a room; and the object of the invention is to simplify the construction of the above-mentioned class of fire-places, thus enabling them to be manufactured at a greatly reduced cost and set up for use without 25 the necessity of building an arch in the wall of a room to receive the fire-place, thus adapting it for use in the same manner as an ordinary stove placed upon any portion of the floor. These objects I attain by the construction 30 substantially as shown in the drawings and hereinafter described and claimed.

In the accompanying drawings the fire-place, which is constructed wholly of sheet metal, is composed of the plate A, bent at 35 right angles to form the sides B, said plate and sides being suitably connected to the metal hearth C, which is supported above the floor by legs *a*. The front plate, D, is also provided with sides E, which form the interior sides of 40 the fire-place, while the plate D forms the back. The sides E are each provided with a flange, *b*, running or extending its entire length, and bent in an outward direction for convenient attachment to the edges of the sides B, so that 45 a continuous closed space, *c*, is formed between the sides B E and plates A D, thus forming a hollow back and sides to the fire-place. A top plate, F, is connected to the upper edges of the plates A D and sides B E, and is formed 50 with a flange, *d*, extending down in front of the fire-place and fastened thereto. This plate

F has a line of perforations, *e*, on the same vertical plane with the space formed by the plates A D and their sides, to allow the free escape of the air, as it becomes heated in the 55 space *c*, into the room, or conducted by pipes or any suitable means to the place desired. In order to more effectually heat the air previous to its escaping through the perforations *e*, the plate D, at its upper end, is bent outwardly, as shown at *k*, so that it will increase 60 the heating-surface of the plate, and also render the back of the fire-place much stronger.

Under the hearth C and to the same is suitably fastened a plate, G, said plate being 65 formed with L-shaped flanges *f* around its four sides, so that when it is connected by said flanges to the under side of the hearth a chamber, *g*, will be formed to receive the fresh air from a pipe, *h*, communicating with the chamber and extending to some convenient point outside the house or other structure. As the 70 fresh air passes through the pipe *h* into the chamber G it is heated by coming in contact with the hearth C, upon which the fire is built. 75 The air, in its course, passes through the perforations *i* into the space *c*, formed by the hollow back and sides of the fire-place, from whence it escapes into the room, or is conducted 80 to the place desired through the perforations *e* in the top plate, F.

The manner of constructing the fire-place by the employment of the metal plates A D, bent to form the sides B E, and connected together and to the hearth C and top plate, F, 85 forms a very simple, durable, and portable fire-place, with a continuous space at its back and sides, and the peculiar construction of the plate G enables it to be readily attached to the hearth C to form the chamber. 90

A fire-place constructed in accordance with my invention insures the radiation of the heat from all sides, as well as at the bottom of the hearth, and is retained and utilized for warming purposes. 95

It should be noticed that the legs *a* retain and support the hearth C above the floor, and the fire-place, consisting of the several plates hereinbefore described, is riveted to the hearth, the sides of the plate A having lugs *l* for this purpose, the hearth extending some distance beyond the front, back, and sides of the fire- 100

place, as shown in Fig. 1, thus forming a wide base or support, and the legs *a* raising the hearth or supporting it above the floor enables the fire-place to be used in any part of 5 a room, the same as an ordinary wood or coal stove, without the necessity of setting it in an arch formed in the wall.

Having now fully described my invention, what I claim as new, and desire to secure by 10 Letters Patent, is—

1. In a fire-place, the sheet-metal plate A, bent to form sides B, and provided with lugs *l*, in combination with the plate D, bent to form the sides E, and again to form the flanges 15 *b*, whereby the plates are connected together to inclose an air-space between them, in connection with the hearth C and the top plate, F, substantially as and for the purpose set forth.

2. A fire-place formed of sheet metal, consisting of the hearth C, having perforations *i*, the plate G, having L-shaped flanges *f* for connecting it to the hearth, the perforated top plate, F, bent downward at its front edge to form flange *d*, the plate A, bent to form sides 20 B, and having lugs *l*, and the plate D, bent to form sides E and flanges *b*, said plates being connected together and to the hearth, substantially as and for the purpose specified. 25

In testimony that I claim the above I have 30 hereunto subscribed my name in the presence of two witnesses.

HENRY REMBERT.

Witnesses:

C. C. MATTHEWS,
C. GREEN.
